UNITED STATES PATENT OFFICE

NILS A. WAHLBERG, OF DERRY, PENNSYLVANIA, ASSIGNOR TO WESTINGHOUSE ELECTRIC & MANUFACTURING COMPANY, A CORPORATION OF PENNSYLVANIA

CONDUCTOR CLAMP

Application filed September 13, 1928. Serial No. 305,732.

My invention relates to conductor clamps and particularly to clamps for suspending high-voltage transmission-line conductors or cables.

One object of my invention is to provide a device of the above-indicated character that shall be constructed of readily renewable parts.

Another object of my invention is to provide a conductor clamp that shall embody a member for selective cooperation with other members which may be of different sizes and shapes.

Another object of my invention is to provide a multi-part clamp that shall have a single means for securing the parts to each other and clamping a conductor relative thereto.

A further object of my invention is to provide a conductor suspension clamp that shall be simple and durable in construction, economical to manufacture and effective in its operation.

In suspending high voltage transmission line conductors or cables, it has been usual to provide clamps having conductor-receiving members of substantially channel-shape, each constructed of one integral piece.

While such channel members may accommodate cables of slightly different diameters, it is generally necessary to construct them of different sizes for conductors of appreciably different diameters. Such channel members have also been constructed of variable lengths in accordance with various conductor diameters and service conditions.

Thus, by having the channel member of one integral piece, damage to one part may necessitate the scrapping of the entire member and it is necessary to carry a relatively large stock of the members for clamps of different sizes.

In practicing my invention, I provide a multi-part channel member in which one part may be of standard-size and shape and the others of variable sizes and shapes, whereby damaged parts may be renewed, without scrapping the entire member, and

clamps of different sizes may be made up from fewer stock parts.

Further, since the member is made up of smaller and simpler component parts, it requires less complicated dies or molds and is accordingly, of easier and more economical manufacture than a similar member in which the parts are integrally united.

Figure 1 of the accompanying drawings is a top plan view of a clamp constructed in accordance with my invention.

Fig. 2 is a side elevational view of the clamp shown in Fig. 1.

Figs. 3, 4, 5 and 6 are detail views of parts of the clamps shown in the other figures, and

Figs. 7 to 12, inclusive, are views similar to Figs. 1 to 6, respectively, of a modified form of my invention.

Referring to Figs. 1 to 6, inclusive, the device comprises a channel structure 2 for disposition at one side, preferably the underside, of a conductor 3, a clamping shoe 4, for engaging the opposite side of the conductor and clamping bolts 5 that are held in position by lock washers 6 and nuts 7.

The channel structure 2 which, in similar clamps, is ordinarily constructed as one integral or homogeneous member is, in this instance, of multi-part construction comprising a central suspension member or supporting element 9 and renewable or removable end portions 10.

The suspension element 9, as shown more clearly in Figs. 3 and 4, is of substantially U-shape in cross-section having central suspension portions 12 and oppositely projecting lower extensions 14. The element 9 further comprises apertured laterally extending projections 15, longitudinally extending reinforcing ribs 16 and laterally extending reinforcing ribs 17.

The end members 10 are provided with apertured side bosses 19 for disposition over the lugs 15 of the element 9, end surfaces 20 for abutting engagement with surfaces 21 on the element 9 and bottom surfaces 22 for resting position on surfaces 23 of the extensions 14.

In the above described structure, each of the elements 9 and 10 has a conductor re-

ceiving channel portion in alignment with the corresponding portion of the other, and the members 10 have flared portions 25 for preventing fatigue of the conductor 3 resulting from the oscillation thereof.

5 The upper clamping shoe 4, having seat portions 26 for the bolts 5, a grooved under surface 27 and slightly flared end portions 28, is preferably constructed as one integral or homogeneous piece that longitudinally spans the intersections of the longitudinally sectionalized lower channel member 2.

When the parts are assembled, as in Figs. 1 and 2, tightening of the nuts 7 clamps the shoe 4 against the conductor 3 which, in turn, clamps the end portions 10 securely in position against the extensions 14 on the element 9.

20 In the above described structure, the members 10 may be of different lengths and have other characteristics different from the members 10 shown, such as having the flared ends 25 of greater or less curvature in accordance with the service for which they are intended. Also, should any of the parts 9 or 10 become damaged, they may be salvaged or renewed individually, without scrapping the entire channel structure.

30 As shown in Figs. 7 to 12, inclusive, in which corresponding parts are designated by corresponding reference characters, the construction is similar to that above described, with the exception that the intermediate portion of the element 9, instead of having its inner surface constitute a part of the channel for engagement with the conductor 3, is adapted to embrace inner channel extensions 30 on the members 10, which are disposed in end-to-end relation 40 with each other, as indicated by a line 31 in Figs. 7 and 8.

45 By this construction, in addition to the variations permitted in the length of the members 10 and the flares of the end portions 25, the channel may be of relatively widely different diameters to accommodate a greater variety of conductors than in clamps heretofore employed.

50 While I have shown and described particular forms of my invention, changes may be effected therein without departing from the spirit and scope thereof, as set forth in the appended claims.

55 I claim as my invention:—

1. A clamp comprising a multi-part conductor-receiving structure for position at one side of the conductor and common means including an element extending through a plurality of said parts for holding the same together and clamping the conductor relative thereto.

60 2. A clamp comprising a conductor-receiving member, a removable end member therefor and common means for securing said

members to each other and clamping the conductor relative thereto.

3. A clamp comprising a conductor-receiving channel structure including separable portions constituting sections of a continuous channel element. 70

4. A clamp comprising a conductor-receiving channel structure including separable end-to-end related channel sections constituting sections of a continuous channel element. 75

5. A clamp comprising a supporting member, a conductor-receiving member, said members each having a portion at the same side of the conductor, and common means 80 for securing said members to each other and clamping the conductor relative to said receiving member including an element extending through each of said members.

6. A cable clamp comprising an intermediate suspension member embodying a channel portion for supporting the cable and aligned channel members removably secured to said suspension member and projecting oppositely therefrom. 85

7. A cable clamp comprising an intermediate suspension member embodying a lower channel portion for supporting the cable and having oppositely-projecting portions and aligned channel members removably secured to said portions. 90

8. A cable clamp comprising an intermediate suspension member embodying a lower channel portion for supporting the cable, aligned channel members projecting 100 oppositely from said channel portion, and means for securing each of said channel members to said suspension member and clamping a conductor in the channel members. 105

9. A clamp comprising an intermediate suspension member embodying a lower portion of substantially U-shape in cross-section having oppositely-projecting extensions, aligned channel members projecting oppositely from said suspension member, and common means for securing each of said channel members to one of said extensions and clamping a conductor in the adjacent channel member. 110

10. A clamp comprising a conductor-receiving member for position at one side of the conductor and constructed of longitudinal sections, a single member for position at the opposite side of the conductor having 120 portions opposite two of said sections, and means for clamping the conductor and holding said members together. 115

11. A clamp comprising a multi-part conductor-receiving structure for position at one side of the conductor and a single means including an element extending through a plurality of said parts to hold the same together and exert a clamping action on the conductor. 125

12. A cable clamp comprising an intermediate suspension member embodying a cable-supporting channel portion, a cable-receiving channel member opposite each end 5 of said portion and means for clamping the cable to said cable-receiving members.

13. A cable clamp comprising an intermediate suspension member embodying a cable-supporting portion, a cable-receiving member at each side of the suspension member 10 in the direction of the cable and means for clamping the cable to said cable-receiving members.

In testimony whereof, I have hereunto 15 subscribed my name this 4th day of Sept. 1928.

NILS A. WAHLBERG.
